INVENTOR:

John Walter Brown.

UNITED STATES PATENT OFFICE.

JOHN WALTER BROWN, OF EAST SHEEN, ENGLAND.

ELEVATOR.

No. 872,986.

Specification of Letters Patent.

Patented Dec. 3, 1907.

Original application filed February 6, 1904, Serial No. 192,430. Divided and this application filed February 18, 1907.
Serial No. 358,079.

To all whom it may concern:

Be it known that I, JOHN WALTER BROWN, a subject of the King of Great Britain and Ireland, residing at 92 East Sheen avenue, 5 East Sheen, in the county of Surrey, England, civil engineer, have invented new and useful Improvements in Elevators, of which the following is a specification.

In working lifts or elevators, it is common 10 to employ hydraulic motors or electric motors. The former possess great advantages in respect to safety, ease of control and low cost of maintenance; while the latter are remarkable for their economy in cost of work- 15 ing.

The object of my invention is to combine the advantages of both systems.

The accompanying drawing illustrates the application of this invention (a division of 20 my application for Letters Patent filed 6th Feby. 1904, Ser. No. 192430) to a hoisting cylinder E of the ram type, with two or more rams and cylinders. For the balance cylinder, I substitute a set of hydraulic pumps E' 25 driven by electric motors J, and between the controlling-valve and the pumps I provide a by-pass valve M, which may be combined with the controlling valve G, or may be connected to the hand-rope a or other apparatus 30 for working the controlling-valve. The hoisting cylinder E is provided with a ram, or rams e¹ e², for lifting, and a ram, or rams e³, for lowering the cage; the raising and lowering rams being so proportioned as to be of 35 equal displacement. The ram e³ is connected to a sheave B around which the hoist-rope passes, and is thence led to the lift A by way of guide-pulleys B' B'. The counterweight F which is equal to the cage and half the 40 load, or thereabout, is attached to the cross-head e⁴ or to prolongations of the rams e¹ e². The cylinders of the lifting and lowering rams are in communication with the valve 45 chamber g of the controlling valve G by means of pipes g' g² each having two branches leading to the valve-chamber. The delivery pipe g³ and the suction pipe g⁴ of the pump E' are also in communication with the valve-chamber g.

The action is as follows:—The motor and 50 pumps being started, the by-pass valve or pump-suction-valves having been previously opened, the cage A with its load is raised by putting the lifting cylinders having the rams e¹ e² in connection with the delivery pipe g³ of 55 the pumps, and the lowering cylinders having the ram e³ in connection with the suction-pipe g⁴ of the pumps through the controlling valve G, the by-pass M being simultaneously closed. For lowering the cage and load, the 60 communications are of a reverse character; the lowering cylinders being connected to the delivery, and the lifting cylinders to the suction, of the pumps.

To make up for leakage, the suction pipe 65 g⁴ of the pumps is connected with a tank K by means of a pipe provided with a non-return valve b.

For actuating the valves G and M levers a' a² are provided respectively connected to 70 each valve and operated by the hand-rope a passing through the cage.

The cage may, if preferred, be nearly counterbalanced by means of weights arranged independently of the hoisting cylinder. 75

What I claim as my invention and desire to secure by Letters Patent, is:—

In a lift system, the combination, with a suspended cage, a counterbalance for the 80 same and approximately half the load, and raising and lowering cylinders furnished with rams, of a closed hydraulic circuit, a pump, an electrical motor for actuating the same, a main valve, a by-pass for short circuiting the 85 pump, a valve therefor, and a lift-rope for operating said valves, substantially as described.

In testimony whereof I have signed my name to this specification in the presence of 90 two subscribing witnesses.

JOHN WALTER BROWN.
